(57) **CLAIM**

The ornamental design for a leak-proof bag with bubble wrap lining, as shown and described.

DESCRIPTION

FIG. 1 is a front top right side perspective view for a leak-proof bag with bubble wrap lining, showing my new design, in an exploded configuration;

FIG. 2 is a front right side perspective view thereof, in an assembled configuration.

FIG. 3 is a rear left side perspective view thereof;

FIG. 4 is a front elevational view thereof;

FIG. 5 is a rear elevational view thereof;

FIG. 6 is a left side elevational view thereof, the right side elevational view being a mirror image; and,

FIG. 7 is a rear left side perspective view thereof, showing the hook and loop fastener in a folded configuration.

1 Claim, 7 Drawing Sheets
